UNITED STATES PATENT OFFICE.

HANS LUFT, OF PROVIDENCE, RHODE ISLAND.

COUPLER.

Application filed October 28, 1927. Serial No. 229,318.

My catch hook or coupler is intended for detachably connecting the bail of a watch with the end of a wrist band, bracelet, or other wrist embracing band.

5 An object of my invention is to afford an attaching member that will automatically adapt itself to a watch bail of any width so that the wrist encircling member to which my device is attached may be sold independently of the watch.

10 A further object is to lock my coupler upon the bail so securely as to prevent accidental escape from the latter.

15 An added object is to enable the formation of the coupler from metal blanks and without the use of solder.

Further objects are inexpensiveness of construction, strength, and simplicity.

20 My invention consists in such parts and in such combinations of parts as fall within the scope of the appended claims.

25 In the accompanying drawings which form a part of this specification.

Figure 1 is a front elevation of my coupler embodied in a watch bracelet, parts being shown broken away,

30 Figures 2 and 3, reduced plan views of the blanks from which my device is formed,

Figure 4, a front perspective view of the 35 coupler,

Figure 5, an end view of the same,

Figure 6, a rear elevation of the coupler, showing a portion of the rear wall broken away,

Figure 7, a section taken on line 7—7 of Figure 4,

Figure 8, a section on line 8—8 of Figure 7, and

Figure 9, a detail perspective view of one 40 of the hook members.

Like reference characters indicate like parts throughout the views.

In the drawings 10 represents a wrist watch provided with the usual end bails 11, 45 one only of which is herein shown. The bail comprises the bar 12 and end arms 13.

The body of my coupler is bent up into a box from a single blank of thin sheet metal of the form shown in Figure 2 wherein the 50 central portions 17 and 18 ultimately form the front and rear wall respectively of the body, while the lateral wings 19 are the ultimate side walls thereof. The spaced forwardly directed extensions 20 upon the wings 19 when inwardly bent constitute the front end wall of the body. The web por-

tion 21 of the blank connecting the central portions 17 and 18 constitutes, after bending, the rear end wall of the body. The lateral lugs 22 upon the wings 19 are ultimately bent over the rear wall 18 to lock the latter against the wall 20. The end wall 20 is shorter than the side walls consequently forming adjacent the front end wall a marginal slot 24 communicating with longitudinal slots 25 extending partially into the side walls 19. In this instance the wall 21 has end openings 26, and the walls 19 have near their ends holes 27. The front and back walls are in this instance slightly inclined 70 relatively to each other.

Riveted or otherwise fixed in an intermediate portion of the side walls is a transversely disposed rod 28 upon which are mounted two attaching members represented generally by 30 of similar construction, each bent up from the blank shown in Figure 3. In detail, as shown in Figure 9, each member comprises a flat arm 31, integral with whose upper forward edge is a hook comprising a flat laterally bent and extended forwardly projecting broad shank 32, disposed in a plane at right angles to the plane of the arm, and a broad beak portion consisting of a broad arch or bend 34, and a broad tip 35. Upon the free extremity of the tip is a lateral tongue 36. Near the rear end of the arm is a perforation 38, adapted to loosely receive the rod 28. Each member 30 is formed from a flat thin metallic blank. 90 The members 30 are slidably mounted on the rod 28 and the arms 31 are normally pressed against the walls 19 by a helical spring 40 surrounding the rod with its ends abutting against the arms. The portions 32 of the members 30 extend through the guide slots 25 and 24 which assist in maintaining the arms 31 at right angles to the pivot rod 28 and thus prevent cramping or bending when the arms move thereover.

To engage my coupler with a bail, the members 30 are compressed by the operator's thumb and finger sufficiently to admit the beak portions thereof to pass loosely through the bail from front to back, whereupon the spring 40 forces the outer edges of the beak portions 34 against the legs 13 of the bail, and the beaks overlap the rod 12. Thus the members 30 are certain to contact with the legs 11, regardless of the dimension of the particular loop engaged. It will be noted that when the members 30 are

engaged as described, the tongues 36 underlie the loop portions 13, and thus still further insure the members 30 against accidental disengagement from the bail. The casting, and attaching members being formed by merely bending the stamped blanks shown in Figures 2 and 3 is inexpensive and avoids the use of solder.

My coupler may be secured to both ends 10 of any type of bracelet band or chain, and in any convenient manner. As herein illustrated the band consists of a series of connected box links 42 housing slidable yoke shaped links 44 whose legs 45 pass through 15 openings 46 in the front end walls, and through openings 26 in the end wall 21 of the coupler and have lateral pins 48 on their ends pivoted in holes 27 in the adjacent link or coupler. The links are tensioned by spring 50 within the links 42.

The foregoing description is directed solely towards the construction illustrated, but I desire it to be understood that I reserve the privilege of resorting to all the 25 mechanical changes to which the device is susceptible, the invention being defined and limited only by the terms of the appended claims.

I claim:—

- 30 1. In a coupler of the type set forth, a casing provided with a slot in its end and sides, a rod fixed in the sides of the casing, spaced attaching members comprising flat arms provided with perforations to loosely 35 receive the rod, broad laterally extended forwardly projecting hooks integral with the arms extending through the slots, and a spring in the casing for distending the attaching members.
- 40 2. In a coupler of the type set forth, a casing provided with a slot, a guide rod mounted in an intermediate portion of the casing, attaching members spaced from each other comprising arms slidably mounted on 45 the rod, and hooks upon the arms projecting through the slot, lateral tongues upon the ends of the hooks, and a spring in the casing between the attaching members abutting against the arms.

3. In a coupler of the type set forth, a 50 casing comprising a front, a back, a forward end provided with a slot, a rear end provided with spaced openings, sides provided with holes adjacent the openings, link members extending into the casing through 55 the openings, pivot pins on the link members in the holes, a rod fixed in the sides, attaching members spaced from each other slidable upon the rod and extending through the slot, and a spring surrounding the rod 60 engaging the attaching members.

4. In a coupler of the type set forth, a casing formed from a single sheet metal blank comprising a front wall, a rear wall connected by an end wall, wings integral 65 with the front wall constituting side walls, extensions on the forward ends of the side walls inwardly folded constituting a second end wall spaced from the first end wall, and lateral locking lugs upon the side walls 70 embracing the rear wall, a transverse rod fixed in the side walls, attaching members each formed from a metal blank by bending comprising a flat arm portion provided with 75 a perforation in one end adapted to receive the rod, a laterally and forwardly broadened extending hook shaped portion disposed at right angles to the arm, and a lateral tongue integral with the hook shaped portion and a spring in the casing abutting 80 against the arm portions of the attaching members.

5. In a coupler of the type set forth, the combination with a wrist band and a watch bail comprising a bar and arms, of a casing 85 attached at one end to the strap and provided at its opposite end with a slot, a transverse rod fixed in the casing parallel with the slot, attaching members slidably mounted on the rod projecting through the slot 90 and loosely engaging the bar, and resilient means in the casing for laterally distending the attaching members into contact with the arms.

In testimony whereof I have affixed my 95 signature.

HANS LUFT.
